UNITED STATES PATENT OFFICE.

HARRY E. ADAMS, OF PITTSBURGH, PENNSYLVANIA.

TAP FOR MULTIPLE-CONDUCTOR METALLIC-SHEATHED CABLES.

1,056,483.

Specification of Letters Patent. Patented Mar. 18, 1913.

Application filed January 29, 1912. Serial No. 674,048.

To all whom it may concern:

Be it known that I, HARRY E. ADAMS, a citizen of the United States of America, residing at Pittsburgh, in the county of Allegheny and State of Pennsylvania, have invented certain new and useful Improvements in Taps for Multiple-Conductor Metallic-Sheathed Cables, of which the following is a specification.

10 This invention relates to taps for multiple conductor metallic sheathed cables, the object of the invention being to provide an improved device of this character adapted for use when it is desired to tap some of the 15 conductors of a main cable, and to carry branches of these conductors through a branch cable to some other point.

The present invention comprises an improved device of this character constructed 20 in such manner as to constitute a housing, the metallic sheathing of the main cable forming a portion of the housing.

Further objects and advantages of the invention will be set forth in the detailed description which now follows.

In the accompanying drawing Figure 1 is a perspective view of a tap constructed in accordance with the invention. Fig. 2 is a transverse vertical sectional view thereof. Fig. 3 is a detailed perspective view showing the main cable split, as herein-after described. Fig. 4 is a side elevation of a portion of the tap. Fig. 5 is a side elevation illustrating the device in use upon a 35 water pipe to form a tap between a main conduit and branch conduits, and Fig. 6 is a plan view of the device illustrated in Fig. 4.

Like numerals designate corresponding 40 parts in all of the figures of the drawing.

Referring to the drawing, the numeral 5 designates the metallic sheathing, usually of lead, of a multiple conductor cable, and 6 designates the conductors passing therethrough. A housing casting 7 is provided with a pair of longitudinally extending rails 8, which are spaced from the housing 7 by ribs 9. This leaves channels 10 between the rails 8 and the housing 7, said channels being 50 open both at the top and at the bottom.

In carrying out the invention, the metallic sheathing 5 is split and the walls of the sheathing upon opposite sides of the split portion, are bent outwardly as at 11 in Figs. 55 2 and 3. The upper edges of these outwardly bent portions enter the channels 10.

Since the splitting of the cable opens the top thereof and exposes the wires, it is apparent that any desired number of the conductors may then be tapped by branch conductors 12 60 and carried off to any desired point through an outlet 13 and branch cable 14. Internally threaded openings 15 are formed in the face of the housing 7 and may be closed when desired by plugs 16. These openings 65 permit the filling of the interior of the housing with paraffin, or any desired plastic composition, after the proper connections have been made between the branch conductors 12 and the main conductors 6. 70

To form a fluid and moisture proof joint between the housing 7 and the upper edges of the walls 11 of the sheathing, solder indicated at 17 in Fig. 2, is poured into the channels 10. This seals the housing along 75 its sides. To seal the housing member 7 to the cable at its ends, saddles 18 are supported by ribs 19 from the housing, and the upper faces of these saddles are cut away at 21 for the reception of molten solder, which, 80 when poured into recesses 21 seals the ends of the housing to the cable. This tap may, if desired, be employed for the purpose of connecting the branch water pipes to water mains, and such a structure has been illustrated in Fig. 5, wherein numeral 5^a designates the main water pipe and 6^a designates the housing. The structure is otherwise the same as that shown in Fig. 2, and the method of connecting the housing 6^a to the 85 pipe 5^a is the same. In this case, 23 designates branch water pipes which may be connected to the upper portion of the housing in place of the plugs 16. At this time it is apparent that a fluid tight joint is made between the housing 6^a and the main 5^a, and that water may be conducted through these pipes to any desired point. This is particularly advantageous where it is desired to 90 connect a plurality of laundry tubs, for instance, to the water main, these tubs being located close enough together to render it desirable to take off a plurality of branch pipes at adjacent points. For this latter purpose, the structure herein described is 95 entirely efficient. 100

From the foregoing description it will be seen that simple and efficient means are herein provided for accomplishing the objects of the invention, but while the elements 11 shown and described are well adapted to serve the purposes for which they are im-

tended, it is to be understood that the invention is not limited to the precise construction set forth, but includes within its purview, such changes as may be made within the scope of the appended claims.

Having described my invention, what I claim is:—

1. In a device of the character described, the combination with a conduit split longitudinally and having its walls bent outwardly upon opposite sides of said split portion, of a housing member having a longitudinally extending channel formed therein upon opposite sides, said channel being open both at the top and at the bottom, and in which channels the upper edges of the bent out portions of the conduit enter.
2. In a device of the character described, the combination with a conduit split longitudinally and having its walls bent outwardly upon opposite sides of said split portion, of a housing member having a longitudinally extending channel formed therein upon opposite sides, said channel being open both at the top and at the bottom, in which channels the upper edges of the bent out portions of the conduit enter, and a fusible sealing filling for said channel for sealing the housing to the conduit.
3. In a device of the character described,

the combination with a conduit split longitudinally and having its walls bent outwardly upon opposite sides of said split portion, of a housing member having a longitudinally extending channel formed therein upon opposite sides, said channel being open both at the top and at the bottom, in which channels the upper edges of the bent out portions of the conduit enter, and a fusible sealing filling for said channel for sealing the housing to the conduit, there being an opening formed in said housing member and a closure for said opening.

4. In a device of the character described, the combination with a conduit split longitudinally, and having the material thereof bent outwardly upon opposite sides of said split portion, of a housing member open at the bottom and having channels formed in its opposite lower edges which are open both at the top and at the bottom and in which channels the upper edges of the bent out portions of the conduit enter.

In testimony whereof I affix my signature in presence of two witnesses.

HARRY E. ADAMS.
